Primary Examiner — Ian Simmons*Assistant Examiner* — Dana L Meyrow(74) *Attorney, Agent, or Firm* — James E. Oehlenschlager(57) **CLAIM**

We claim the ornamental design for a bottle, as shown and described.

DESCRIPTION

FIG. 1 is a front perspective view showing our new design for a bottle;

FIG. 2 is a front elevational view thereof;

FIGS. 3 and 4 are side elevational views thereof;

FIG. 5 is a rear elevational view thereof;

FIG. 6 is a top plan view thereof; and

FIG. 7 is a bottom view thereof;

FIG. 8 is a front perspective view showing an alternate embodiment of our new design for a bottle, the stippling being indicative of an opaque surface;

FIG. 9 is a front elevational view thereof;

FIGS. 10 and 11 are side elevational views thereof;

FIG. 12 is a rear elevational view thereof;

FIG. 13 is a top plan view thereof; and,

FIG. 14 is a bottom view thereof.

The broken lines shown in the drawings depict environmental subject matter only and form no part of the claimed design.
